Inventor:

Mary Belle La Roe.

UNITED STATES PATENT OFFICE

128,050

DESIGN FOR A CHRISTMAS STOCKING

Mary Belle La Roe, Terrell, Tex.

Application November 29, 1940, Serial No. 96,961

Term of patent 3½ years

To all whom it may concern:

Be it known that I, Mary Belle La Roe, a citizen of the United States, residing at 302 Grace Lane, Terrell, in the county of Kaufman and State of Texas, have invented a new, original, and ornamental Design for a Christmas Stocking, of which the following is a specification, reference being made to the accompanying drawing, forming part thereof.

I claim:

The ornamental design for a Christmas stocking, as shown.

MARY BELLE LA ROE.
